UNITED STATES PATENT OFFICE

HENRY FUCHS, OF CHICAGO, ILLINOIS, ASSIGNOR TO W. H. MINER, INC., OF CHICAGO,
ILLINOIS, A CORPORATION OF DELAWARE

HAND BRAKE

Application filed October 15, 1930. Serial No. 488,826.

This invention relates to improvements in hand brakes.

One object of the invention is to provide a simple and efficient hand brake mechanism of the rotary type, including a rotary winding member and means for actuating the same, wherein the latter is held against backward rotation and means is provided for disconnecting the actuating means from the winding means to effect release of the brakes, thereby permitting free rotation of the winding means in unwinding direction without imparting rotation to the actuating means, entirely eliminating spinning thereof, and protecting the brakeman against injury.

A more specific object of the invention is to provide, in a hand brake mechanism of the character indicated in the preceding paragraph, releasable clutch means between the actuating means and the winding means, which clutch means is carried entirely by the operating hand wheel, whereby the hand wheel unit, including the releasing means, may be employed in connection with any type of rotary brake mechanism, as for example, a brake wherein the hand wheel directly operates a staff on which the chain is wound, a brake mechanism wherein the hand wheel actuates gear means cooperating with gear means fixed to the winding drum, and all other types of brakes driven by a rotary shaft.

Other objects of the invention will more clearly appear from the description and claims hereinafter following.

In the drawing, forming a part of this specification, Figure 1 is a vertical, sectional view through the vertical end wall of a railway car illustrating my improvements in connection therewith. Figure 2 is a vertical, sectional view, corresponding substantially to the line 2—2 of Figure 1, said view being on an enlarged scale and a certain cover plate shown in Figure 1 being removed. Figure 3 is a transverse, sectional view, corresponding substantially to the line 3—3 of Figure 2. Figure 4 is a transverse, sectional view corresponding substantially to the line 4—4 of Figure 2. Figure 5 is a sectional view corresponding substantially to the line 5—5 of Figure 2. And Figure 6 is a transverse, ver-

tical, sectional view corresponding substantially to the line 6—6 of Figure 1.

In said drawing, 10 designates the vertical end wall of a railway car, on which my improved hand brake mechanism is mounted. 55 As clearly illustrated in Figure 1, the operating mechanism proper is preferably contained within a housing comprising sections 11 and 12. The section 12 is in the form of a plate forming the back wall of the housing and the section 11 is in the form of a cover member secured to said back wall, the cover member and the back wall being provided with aligned lugs through which securing rivets 13 extend, the rivets preferably also being employed to fix the housing to the end wall 10 of the car. The housing is open at the bottom, as clearly shown in Figure 1, so as to accommodate the brake chain 14 for movement. The brake chain is connected to the 70 brake mechanism proper of the car in the usual manner.

My improved brake mechanism comprises broadly a chain winding drum A; a drum gear B; an operating shaft C; a drive gear D; a hand wheel E; a clutch element F; a carrier ring G; a plurality of clutch fingers H—H; a releasable clutch locking means K; a ratchet L, and a releasable locking dog M.

The chain winding drum A is of well known form and is preferably fixed to a supporting shaft 14 rotatably journaled in bearing openings 15—15 provided in the front and rear walls of the housing. As shown, the central portion of the shaft 14 is of square cross section and fits within square openings provided in the hub of the drum member, whereby the drum member is fixed to the shaft for rotation in unison therewith. As shown, the drum member is of conical form and has the gear member B formed integral therewith. The chain 14 is secured to the drum by means of a bolt 16 extending through an outstanding lug 17 on the drum, through the end link of the chain, and an opening provided in the web portion of the gear member B.

The operating shaft C is journaled in the front and rear walls of the housing, and as

shown is provided with a head 18 at the inner end thereof, seated in a hollow boss on the rear wall 12 of the housing, whereby the shaft is held against endwise movement. The shaft C has the drive gear D fixed thereto, the same being secured by any suitable means, preferably a key. The gear D meshes with the gear B, thereby being in operative driving relation therewith, both during the chain winding operation and during the unwinding operation in release of the brakes. The shaft C extends through the front wall of the housing and has the hand wheel E mounted thereon. As most clearly shown in Figures 2, 3 and 4, the shaft C has the clutch section F formed adjacent the outer end thereof, the clutch section being of substantially cylindrical form and having a plurality of peripheral wedge faces 20-20. The wedge faces 20, as shown in Figure 2, are preferably four in number and are equally spaced. Each of these faces are arranged at a relatively keen wedging angle with respect to a plane perpendicular to a radial plane of the shaft C. The hand wheel E is provided with a sleeve-like hub section 21 surrounding the shaft C. At the outer end the sleeve-like section 21 is enlarged, as indicated at 22, and forms a housing for the carrier ring G, which cooperates with the clutch element F. As shown, the carrier ring G is freely rotatable within the enlarged portion 22 of the sleeve-like hub section of the hand wheel E and about the outer end portion of the shaft C. The carrier ring is held within the hub by means of a cover plate 23 fixed to the outer face of the hub. The enlarged portion 22 of the hub section is provided with four radially disposed, interior pockets 24-24. The pockets 24 are equally spaced and each has a radial wall 25 and an inclined wall 26. The ring G is provided with four radially disposed guideways 27-27 within which the clutch fingers H-H are slidable. Each clutch finger H extends entirely through the ring G and has wedge faces at the opposite ends thereof, correspondingly inclined to and cooperating with the wedge faces 20 and 26 of the element E and the enlarged portion 22 of the hub section of the hand wheel. As clearly shown in Figure 2, the wedge faces 26 are inclined at keener angles than the wedge faces 20. The pockets 24 are of greater width than the corresponding ends of the clutch fingers H, whereby lateral motion of the clutch fingers with respect to said pockets is permitted. The hub section 22 is also provided with a pair of diametrically opposed, interior openings 28-28 providing spaced limiting shoulders 29-29. The ring G has a pair of diametrically opposed stop lugs 30-30 operating in the recesses 28-28. As most clearly shown in Figure 5, each stop lug has a flat side face 31 and is beveled at the top, as indicated at 32. A releasable lock-

ing member K cooperates with the two lugs 30-30 of the ring G. The locking member is of U-shape form having a pair of spaced arms 33-33 slidable in alined openings in the enlarged hub section 22 and the cover plate 23. The arms 33 extend through the opposed openings of the hub section 22 and have their outer ends reduced, as indicated at 34, said reduced ends having coiled springs 35-35 mounted thereon, which cooperate with the inner face of the enlarged portion 22 of the hub and nut members at the outer ends of the arms. The portions 33 of the arms extending through the openings 28-28 of the hub section 22 are of such a thickness that when the arms are in their innermost position, the same fill the space between the lugs 30 of the ring G and the opposed shoulders 29-29 on the hub section 22, as clearly shown in Figure 5. The portion between the section of each arm last referred to and the reduced outer end thereof is beveled, as indicated at 36, so as to cooperate with the beveled portion 32 of the corresponding lug to force the ring G backwardly in case the same is not completely returned in the releasing operation of the brakes. Inward movement of the arms 33 of the U-shaped locking means K is limited by collars 37-37 cooperating with the cover plate 23 of the hub of the hand wheel. The springs 35-35 normally hold the locking member K in the innermost position.

Backward rotation of the hand wheel E and the chain winding drum when operatively connected thereto is prevented by the cooperating ratchet L and locking dog M. The ratchet member L is formed integral with the inner end portion of the sleeve of the hub of the hand wheel, as clearly shown in Figures 1, 3 and 4. The locking dog is gravity actuated and is suitably pivoted on the front wall of the housing by means of a pivot pin 38.

The operation of my improved hand brake mechanism is as follows: With the parts in the position shown in the drawing, that is the releasable clutch means K in its innermost position, the clutch fingers H-H are held in clutching engagement with both the clutch element F of the shaft C and the hub section of the hand wheel E. As will be evident, due to the tight clutching engagement provided, rotation of the hand wheel E in a clockwise direction, as viewed in Figure 2, will effect rotation of the driving shaft C in a similar direction and through the cooperating gears D and B, rotation will be imparted to the drum A in a contra-clockwise direction, thereby winding the chain 14 thereon and tightening the brakes. In releasing the brakes, the locking member K is pulled outwardly against the tension of the springs 35-35, thereby bringing the reduced portions of the arms into alinement with the

lugs 30—30 of the ring G. Due to the pull of the brake chain in unwinding direction, the shaft C will be forced to rotate in a contra-clockwise direction, thereby forcing the clutch fingers H—H radially outwardly. Such movement of the clutch fingers is permitted by the cooperating wedge faces of the fingers and the hub section of the hand wheel and by the rotative movement of the ring G in a clockwise direction, as viewed in Figure 2. As will be understood, rotation of the ring G is permitted, due to the arms 33 of the clutch locking means having been pulled outwardly, thereby permitting the necessary movement in a clockwise direction of the lugs on the ring G.

During this releasing action, the hand wheel will be positively held against backward rotation by means of the locking dog M cooperating with the ratchet L on the hub of the hand wheel. Spinning of the hand wheel in release is thus positively eliminated, thereby protecting the brakeman against injury.

In again tightening the brakes, the hand wheel E is rotated in a clockwise direction, thereby causing the fingers H to rotate therewith, the ring G being moved with the fingers. As this movement continues, the fingers H will be brought into registration with the wedge faces on the clutch element of the shaft C. On account of the wedging action between the wedge faces 26 of the hub 22 of the hand wheel and the outer wedge faces of the fingers H, the latter will be forced inwardly into tight engagement with the wedge faces of the clutch element F. During this time the ring G will back up to the position shown in Figure 2 and the clutch locking means K will be pulled inwardly by the springs 35—35, thereby again bringing the thicker portions of the arms 33 into opposed relation to the lugs 30—30 of the ring G and locking the ring against rotation with respect to the hand wheel. When the parts are thus tightly locked together, the mechanism is again in the operative position hereinbefore described and the brakes are tightened in the manner hereinbefore referred to.

I have herein shown and described what I now consider the preferred manner of carrying out my invention, but the same is merely illustrative and I contemplate all changes and modifications that come within the scope of the claims appended hereto.

I claim:

1. In a hand brake, the combination with a rotary chain winding member; of means for rotating said member, including a rotary shaft; a hand wheel; and clutch means for operatively connecting the hand wheel and shaft, said clutch means including clutch fingers having clutching engagement with the shaft, and means actuated by rotation of the

hand wheel in chain tightening direction for operating said fingers to clutch the shaft.

2. In a hand brake, the combination with a rotary chain winding member; of means for rotating said member, including a rotary shaft; a hand wheel; clutch means for operatively connecting the hand wheel and shaft, said clutch means including clutch fingers having clutching engagement with the shaft, and means actuated by rotation of the hand wheel in chain tightening direction for operating said fingers to clutch the shaft; and releasable means for locking said clutch means in operative position.

3. In a hand brake, the combination with a rotary chain winding member; of means for rotating said member, including a rotary shaft; a hand wheel; clutch means for operatively connecting the hand wheel and shaft, said clutch means including clutch fingers having clutching engagement with the shaft, and means actuated by rotation of the hand wheel in chain tightening direction for operating said fingers to clutch the shaft; releasable means for locking said clutch means in operative position; and means actuated by rotation of said winding means in unwinding direction for disengaging said clutch fingers when said locking means is released.

4. In a hand brake, the combination with a rotary chain winding member; of means for rotating said member, including a rotary shaft; a hand wheel; clutch means for operatively connecting the hand wheel and shaft, said clutch means including clutch fingers having clutching engagement with the shaft, and means actuated by rotation of the hand wheel in chain tightening direction for operating said fingers to clutch the shaft; releasable means for locking said clutch means in operative position; means actuated by rotation of said winding means in unwinding direction for disengaging said clutch fingers when said locking means is released; and means for preventing backward rotation of said hand wheel while said clutch is being released.

5. In a hand brake mechanism, the combination with a rotary shaft, said shaft having wedge faces; of a carrier rotatable about said shaft; an operating hand wheel having a hub portion rotatable about said carrier, said hub portion having a plurality of wedge faces thereon; and a plurality of sliding clutch fingers mounted on said carrier and having wedging engagement at opposite ends with said wedge faces of said shaft and hub portion respectively.

6. In a hand brake mechanism, the combination with a rotary shaft through which the brake is actuated, said shaft having wedge faces thereon; a carrier rotatable about said shaft; an operating hand wheel having a hub portion rotatable about said carrier, said hub portion having a plurality of wedge faces

thereon; a plurality of sliding clutch fingers mounted on said carrier and having wedging engagement at opposite ends with said wedge faces of said shaft and hub portion respectively; and releasable means for locking said carrier to said hub portion with the fingers in clutching engagement with said shaft.

7. In a hand brake mechanism, the combination with a rotary shaft having a cylindrical clutch section; a ring journaled on said clutch section; a hand wheel having a sleeve portion journaled on said ring; a plurality of fingers radially slidable in said ring, each of said fingers having clutching engagement at opposite ends with said ring and sleeve respectively, the cooperating wedge faces of said sleeve and finger being keener with respect to the longitudinal axis of said finger than the cooperating faces of said clutch section and finger.

8. In a hand brake mechanism, the combination with a rotary shaft having a cylindrical clutch section; a ring journaled on said clutch section; a hand wheel having a sleeve portion journaled on said ring; a plurality of fingers radially slidable in said ring, each of said fingers having clutching engagement at opposite ends with said ring and sleeve respectively, said ring having lugs having shouldered engagement with said sleeve for limiting the rotation of said ring and sleeve; and a releasable locking member cooperating with said lugs for locking the ring and sleeve against relative rotation.

9. In a hand brake mechanism, the combination with a rotary shaft having a cylindrical portion provided with a plurality of peripheral wedge faces; of a ring journaled on said portion, said ring having radial guideways therein corresponding in number to said wedge faces; a hand wheel having a sleeve-like hub section journaled on said ring, said sleeve-like section having a plurality of interior pockets therein, corresponding in number to said wedge faces, each pocket having a wall thereof provided with a wedge face; a clutch finger slidable in each guideway of said ring, each clutch finger extending into one of said pockets and having wedging engagement with the wedge face of said cylindrical enlargement and the hub section, said finger being laterally movable in said pocket, said ring having a lug thereon cooperating with spaced shoulders on said hub section for limiting relative rotation of said ring and hub section; and releasable locking means adapted to be interposed between said lug and one of said shoulders on said hub section for locking the ring to said section, thereby holding the clutch finger in clutching engagement with the hub section and said cylindrical portion of the rotary shaft.

10. In a hand brake mechanism, the combination with a rotary shaft having a cylindrical portion provided with a plurality of

peripheral wedge faces; of a ring journaled on said portion, said ring having radial guideways therein corresponding in number to said wedge faces; a hand wheel having a sleeve-like hub section journaled on said ring, said sleeve-like section having a plurality of interior pockets therein, corresponding in number to said wedge faces, each pocket having a wall thereof provided with a wedge face; a clutch finger slidable in each guideway of said ring, each clutch finger extending into one of said pockets and having wedging engagement with the wedge faces of said cylindrical portion and the hub section, said finger being laterally movable in said pocket, said ring having a lug thereon co-operating with spaced shoulders on said hub section for limiting relative rotation of said ring and hub section; a releasable locking means adapted to be interposed between said lug and one of said shoulders on said hub section for locking the ring to said section, thereby holding the clutch fingers in clutching engagement with the hub section and said cylindrical portion of the rotary shaft; a ratchet member fixed to said hand wheel; and a releasable dog cooperating with said ratchet member.

In witness that I claim the foregoing I have hereunto subscribed my name this 10th day of October, 1930.

HENRY FUCHS.
